United States Patent Office

Des. 185,992

Patented Aug. 25, 1959

185,992

JEWELRY BOX OR SIMILAR ARTICLE

Vladimir A. D'Arbeloff, Riverside, Conn.

Application October 9, 1958, Serial No. 52,920

Term of patent 7 years

(Cl. D58—12)

Fig. 1

Fig. 2

Fig. 1 is a side perspective view of a jewelry box or similar article showing my new design; and

Fig. 2 is a rear perspective view thereof shown in partially open position.

The side not shown is the same as the side shown.

I claim:

The ornamental design for a jewelry box or similar article, substantially as shown and described.
